UNITED STATES PATENT OFFICE.

WILLIAM L. PATTERSON, OF ROCHESTER, NEW YORK, ASSIGNOR TO BAUSCH & LOMB
OPTICAL COMPANY, OF ROCHESTER, NEW YORK, A CORPORATION OF NEW YORK.

ARC-LAMP.

1,129,117.

Specification of Letters Patent.

Patented Feb. 23, 1915.

Application filed June 8, 1912. Serial No. 702,436.

To all whom it may concern:

Be it known that I, WILLIAM L. PATTERSON, of Rochester, in the county of Monroe and State of New York, have invented certain new and useful Improvements in Arc-Lamps; and I do hereby declare the following to be a full, clear, and exact description of the same, reference being had to the accompanying drawings, forming a part of this specification, and to the reference-numerals marked thereon.

The present invention relates to arc lamps, with particular reference to lanterns in which the electrodes are manually adjusted, and it has for its object to provide mechanism for moving the electrodes simultaneously toward or from each other.

A further object of my invention resides in a novel construction and arrangement of parts which enables the electrodes to be readily positioned, and to be slidably held in operative relation with each other.

Still another object of my improvement consists in providing means for feeding the electrodes in directions at angles to each other, they being held yieldably in engagement with the feeding devices, so that they may be moved independently, when desired.

To these and other ends the invention consists in certain improvements and combinations of parts all as will be hereinafter more fully described, the novel features being pointed out in the claims at the end of the specification.

In the drawings: Figure 1 is a side elevation of a lamp constructed in accordance with one embodiment of the invention; Fig. 2 is a front view of the same; Fig. 3 is a vertical sectional view on the line 3^a—3^a of Fig. 2; Fig. 4 is a transverse sectional view on the line 4^a—4^a of Fig. 1; Fig. 5 is a detail view in elevation showing one of the electrode holders, and Fig. 6 is a detail sectional view through one of the electrode actuating members, and its support.

Similar reference numerals throughout the several figures indicate the same parts.

In the present embodiment of the invention, A designates a lamp body, such as used for lanterns in projecting apparatus and similar machines, and B are the carbon electrodes, preferably disposed at right angles to each other, as shown. The electrodes are arranged to be moved by suitable actuating

members, which preferably comprise the 55 rolls 1. Said rolls have annular grooves 2 formed thereon to engage the electrodes, the grooves being transversely corrugated at 3 so as to grip the electrodes with sufficient force to effect movement thereof. The rolls 60 1 are constructed of porcelain or other suitable insulating material, and are suitably mounted on arbors 4, preferably by means of pins 5 extending through the arbors and arranged in coöperating recesses in the rolls. 65 Also mounted on the arbors 4 are the pinions 6 arranged to mesh with each other, as shown in Fig. 2. The arbors are mounted in suitable bearings 7 formed in the lamp body A, and may be rotated in any suitable 70 manner as by means of a hand piece 8 secured to the end of one of the arbors, which is extended through the lamp body for this purpose as shown.

The electrodes are mounted in holders 9 75 which are pivotally mounted at 10 on the supports 11, the latter being suitably attached to the lamp body and insulated therefrom. The supports 11 are provided with recesses in which are mounted the springs 80 12, arranged to engage the holders 9 so as to move the latter on the pivots 10, away from the lamp body, and thus normally effecting engagement between the electrodes and the rolls 1. Connections are made with the 85 holders 9 by means of the openings 13 and set screws 14. By this construction, it will be seen that either electrode may be moved independently of the other by forcing it slightly away from its actuating member, 90 against the tendency of the spring 12, and sliding it in its holder. When in their normal positions, as shown in Fig. 4, simultaneous movement of the electrodes is effected by turning the hand piece 8, which moves 95 both actuating members, and likewise the electrodes by reason of their frictional engagement with the corrugated surface of the rolls.

While I have shown the invention as applied to a lamp embodying electrodes arranged at right angles to each other, its application is not limited to this particular type of lamp, but it may be adopted with electrodes arranged at any angle to each 105 other or, where they are in alinement.

I claim as my invention:

1. In an arc lamp, the combination with

- a pair of electrodes, of rolls in engagement with the electrodes and connected together for simultaneous movement, holders for supporting the electrodes against said rolls, the holders being pivotally mounted to swing in the plane of the rolls, and springs in engagement with the free portions of the holders whereby to force the latter normally in a direction so as to effect contact between the electrodes and the rolls.
2. In an arc lamp, the combination with a pair of electrodes, of rolls in engagement with the electrodes and connected together for simultaneous movement, holders for supporting the electrodes against said rolls, the holders being pivotally mounted to swing in the plane of the rolls, and means coöperating with the holders and actuating them so

as to effect contact between the electrodes and the rolls.

3. In an arc lamp, the combination with a pair of electrodes, of rotary actuating members in engagement with the electrodes, means connected with the actuating members and operating to rotate them simultaneously, holders for supporting the electrodes against the actuating members, the holders being pivotally mounted to swing in the plane of the rolls, and means coöperating with the holders and acting to effect contact between the electrodes and the actuating members.

WILLIAM L. PATTERSON.
